UNITED STATES PATENT OFFICE.

SYDNEY W. TREAT, OF CHICAGO, ILLINOIS, ASSIGNOR TO SIGNODE SYSTEM INC., OF CHICAGO, ILLINOIS, A CORPORATION OF DELAWARE.

SEAL.

Application filed April 29, 1920. Serial No. 377,697.

To all whom it may concern:

Be it known that I, SYDNEY W. TREAT, a citizen of the United States, and resident of Chicago, in the county of Cook and State 5 of Illinois, have invented a certain new and useful Improvement in Seals, of which the following is a full, clear, concise, and exact description, reference being had to the accompanying drawings, forming a part of 10 this specification.

This invention relates to means for sealing freight cars and other containers to render pilfering impossible without detection.

15 It is an object of the invention to provide simple efficient means for this purpose, which shall be simple and economical to manufacture and apply.

In the accompanying drawings, which 20 represent an illustrative embodiment of the invention:

Fig. 1 is a perspective view of a seal made according to my invention.

25 Fig. 2 is a perspective view of the sealing means with its coacting elements separated.

30 Fig. 3 is a plan view of a piece of sheet metal stock showing how the sleeve element of the sealing means may be produced without waste.

35 Box car seals of the prior art have comprised generally, either lead seals, which are expensive, or some form of sheet metal device, which involves the cutting out of special forms, involving substantial waste of metal. In the sheet metal sealing means herein disclosed, no waste is involved, and the device is otherwise advantageous.

40 I employ coacting elements, one a strip 1 of sheet metal which may be threaded through a staple, or other device on a box car door, for instance; the sleeve 2, which is adapted to be crimped upon and simultaneously with the two ends of the strip, forming therewith a pilfer proof seal.

45 The metal strip 1, may be cut in indefinite lengths from sheet metal stock without waste since it is of uniform width throughout. The sleeve element 2 comprises a portion having folded wings 3, to form a slotted tube appropriately formed to receive superposed ends of the strip 1, and a tab or extension 4. In Fig. 3, it is shown that the blanks for forming the sleeve elements may 50 be cut from sheet metal stock without

waste—each tab 4 lying between the wider portions of the adjacent blanks on each side. The dotted lines in Fig. 3 indicate where the wings 3 are folded over on each blank to form the sleeve portion as shown in 60 Fig. 2.

In assembling a box car seal constructed according to this invention, a strip 1, of predetermined length is threaded through a staple or the like on a car door; its ends 65 are then superposed and threaded together in the same direction through the sleeve 2. Thereafter by a suitable tool, the assembly, comprising the two strips and the sleeve, 70 is simultaneously crimped, in a manner to distort the edges of the assembly toward each other, and form a joint such as that illustrated in Fig. 1, and shown more in detail in Flora Patent 1,252,680 of January 8, 1918.

75 The result is a strong joint which cannot be opened without leaving clear indications of having been tampered with.

It is desirable in applying box seals and the like, that the seal be impressed with 80 the name or device of the railroad or shipper. It is somewhat difficult to do this satisfactorily as the seal is being applied, furthermore the distortion involved as making a sealed joint in sheet metal device, would 85 render such impress difficult to identify. I therefore provide the tab or extension 4, upon which the name (for instance) of the shipper may be impressed, preferably in raised letters, but in any other manner desired. This tab is not involved in the distortion which forms the joint and maintains 90 its legibility unimpaired, throughout the life of the seal. Thus, each shipper may have 95 his own device on the tabs of the sleeve member he uses. In addition the strips 1 may bear in raised letters or otherwise the name of the railroad or of the shipper, or any other desired legend.

100 The foregoing discloses an exceedingly cheap and efficient seal, easily applied and identifiable at all times. Obviously the disclosed seal may be used for many other purposes than for sealing box cars, such use being merely illustrative.

I claim:

1. A seal member of the class described comprising an initially flat rectangular body portion having a narrower tongue formed integral with and projecting cen- 110

trally from one end thereof, both lateral edges of said body member being turned toward each other to provide strip slots parallel with the lateral edges of said tongue.

2. In combination, a metal strip turned upon itself and having its ends brought together, a seal member comprising an initially rectangular flat body portion having its lateral edges turned toward each other to form slots embracing the lateral edges of the ends of said strip, together with a tongue formed integral with and projecting centrally from one end of said body portion, said tongue lying parallel with and against one of the end portions of said strip.
3. A seal member of the class described comprising an initially flat rectangular body portion, and a narrower tongue of the same length as said body portion, said tongue projecting centrally from one end of the body portion with the lateral edges of the tongue and body portion parallel with each other, the lateral edges of the body portion being turned toward each other to provide strip slots for the purpose set forth.

4. A seal of the class described comprising an initially flat substantially rectangular body portion, a narrower tongue integral with said body portion and adapted to have identifying legends applied thereto, the edges of said body portion being folded and rebent in the same direction to provide a sleeve or channel, and a strip of sheet metal, the opposite ends of which are passed into said sleeve in the same direction, said sleeve and said ends being conjointly crimped together.

5. A seal member of the class described comprising an initially flat rectangular body portion having a narrower tongue formed integral with and projecting from one end thereof, both lateral edges of said body member being turned towards each other to form wings substantially parallel with the lateral edges of said tongue, said wings lying in substantially the same plane and being of substantially the same width.

In witness whereof, I hereunto subscribe my name this 15 day of April, A. D., 1920.

S. W. TREAT.
